Application March 3, 1947, Serial No. 731,958
 In Great Britain April 9, 1946

3 Claims. (Cl. 69—34)

1

This invention relates to improvements in leather staking machines, and is herein illustrated as applied to the well-known Slocomb type of staking machine commonly used to soften skins by flexing the same and loosening the fibers. Machines of this type are disclosed in the patents to F. F. Slocomb No. 1,268,637 and C. F. Stackpole No. 1,744,420.

Machines of the above-mentioned type are usually provided with a work table which is divided into two parts separated by a rectangular opening or space between them about nine or ten inches wide. Two long, opposed and cooperating arms or jaws extend toward the operator from the rear of the machine, one of the jaws being located above and the other jaw below the rectangular opening or space in the table. The upper jaw is conventionally provided with a soft member such as a rubber roll at its end and the lower jaw is usually provided with a staking tool such as a blade or a number of blades extending upwardly in the general direction of the rubber roll. When the machine is initially at rest, the jaws are open and in a retracted position to permit the operator to place a work piece upon the table and across the table opening. As the jaws move toward the operator, he shifts an untreated portion of the skin on the surface of the table to a position between the jaws. The jaws then close upon and grip the skin and move rearwardly or away from the operator, the skin being held stationary either by the operator or by means of a clamping device. In so doing the leather is pulled and caused to flex sharply over the blades and around the rubber roll thereby softening the skin. The operator shifts the position of the skin with each forward movement of the jaws in order to treat the full area of the skin. In the case of calfskins the grain surface is usually placed up-
 permost and presented to the rubber roll, the blade acting upon the flesh side. In the case of suede leather, however, the flesh side is generally presented to the rubber roll. In such a machine the leather may be held at one end or edge on a table or bed either by the operator pressing upon the leather itself or upon an appropriate member or by means of work gripping or clamping means adapted to hold the leather during working or rearward strokes and to release it during the idle or forward strokes. The operator is therefore enabled to move the work piece in order to bring the different portions thereof into contact with the leather treating tools and secure uniform treatment of them.

In machines of this type as heretofore con-

2

structed there has been a tendency, when the leather is pulled over the edge or edges of the staking knife or knives for the grain of the leather to be stretched to a greater extent than the flesh side. As a consequence, when the leather is laid flat the grain has appeared to be what is called "pipey." "Pipey" leather is leather the grain surface of which forms coarse, dark and loose wrinkles displeasing to the eye when it is bent with the grain inward. Another defect of such a machine as heretofore constructed is that the edges of the leather have usually been insufficiently treated.

An object of the present invention is to provide an improved machine by the use of which the "pipey" effect is largely eliminated and by the operation of which the edges of the leather may more easily and adequately be treated.

Another object of the invention is to provide an improved leather staking machine which will produce little or substantially no friction on the grain or finished side of the leather being treated.

To this end, and in accordance with an important feature of the invention, an endless resilient belt is mounted upon rotatable rollers and arranged to bear against one side of the leather being treated and to coat with a staking tool or tools bearing against the other side of the leather, the belt and staking means being bodily movable within paths which are in vertical alignment with an opening in a work supporting table. A further feature comprises means for adjusting the operative elements of the machine to vary the effective pressure of the working tools upon the material undergoing treatment.

These and other important features of the invention will be described in detail in the specification and pointed out in the appended claims.

40 In the drawings,

Fig. 1 is a fragmentary side elevational view of so much only of a staking machine of the type concerned as is necessary to illustrate the application thereto of the improved leather staking means of the present invention, a portion of the work supporting table being shown in section;

Fig. 2 is a plan view of one suitable arrangement for the staking tools as they are supported from beneath the work supporting table of the machine;

Fig. 3 is a front view of the staking head as seen in the direction of the arrow in Fig. 1, the table being shown in section; and

Fig. 4 is a detail transverse view partially in section, taken on the line IV—IV of Fig. 1, show-

ing one of two supporting rollers for the endless resilient belt.

A machine known to the trade as the Slocomb type of staking machine includes two horizontal wooden jaws or arms 10 and 12 which are vertically spaced one above the other, as shown in Fig. 1, and are mounted for reciprocation longitudinally toward and away from an operator standing in front of the machine. In addition, the jaws 10 and 12 are relatively movable in a vertical plane alternately to close and open the gap between the operative components attached to the ends of the jaws. In this connection, the jaws are so operated that as the jaw 10 moves downwardly the jaw 12 moves upwardly, and vice versa. The up-and-down as well as the reciprocatory motions of the operative components on the ends of the jaws take place in paths above and below an opening in a table as will subsequently appear.

To the wooden jaw 10 is applied an upper jaw component comprising T-shaped plates 14 and 16 (Fig. 3) pivoted to the end of the arm 10 by means of a bolt 18 which is held in position by washers 20, 22 and lock nuts 24 and 26. An endless resilient belt 30 is supported upon rotative rollers 32, 34 which are rotatably mounted upon the T-shaped plates 14 and 16. The T-shaped plates 14 and 16 constitute protective members for the resilient belt 30 and are formed with upwardly directed arms, which are connected—above the wooden arm 10—by a cross member 36. A threaded bolt 40 is pivoted at one end within a bracket 42 attached to the top of the wooden arm 10 and this bolt 40 extends through the cross member 36 and cooperates with nuts 44 and 46 so that by appropriate manipulation of the latter the upper jaw component can be adjusted in position by causing it to turn bodily about the pivot or bolt 18. Threaded studs 43 and 45 are integral with the member 36 and carry locking nuts 47 and 49. By such means the rollers 32 and 34 may be raised or lowered in relation to the staking tool or tools carried by the lower jaw 12 so as to vary the pressure between the staking tool or tools and the endless belt 30.

As will be seen in Fig. 4 the roller 32 is slightly barrel shaped to maintain the endless resilient belt 30 in a central position thereon. The spindle 50 of the roller 32 is fitted, adjacent to its ends, with square blocks 52 and 54 each adapted to slide into and fit in an open-ended slot. Such a slot is formed in one end of each of the side members or T-shaped plates 14 and 16. Lock nuts 53 and 55 are utilized in the threaded ends of the spindle 50. Similarly, the spindle 56 of the roller 34 is fitted with slideable blocks (only one such block 58 is shown in Fig. 1) but they are arranged within slots (see slot 60 in Fig. 1) formed in the T-shaped plates 14 and 16, which slots are of greater length than the slots for the blocks 52 and 54. The slideable blocks of roller 34 are each associated with, or integral with, adjusting screws (only one such adjusting screw 62 is shown in Fig. 1) which extend through elements (such as element 64), each of the latter being adapted to take a bearing on a rear edge of a T-shaped plate 14 or 16 and to cooperate with lock nuts such as nuts 66 and 68. The last-mentioned elements constitute tensioning devices for adjusting the tension of the belt 30. To remove the belt 30 the nuts such as nuts 66 and 68 are first removed and then the roller 34 is pushed toward the roller 32 as far as permitted

by the slots 60 whereupon the roller 32 is free to be withdrawn from its supporting slots and lowered sufficiently to clear the T-shaped plates 14 and 16. Thereafter, the roller 34 is pushed out through the slots 60.

To enable the endless resilient belt 30 to run with a minimum of friction the roller 32 is mounted on ball bearings 70 (Fig. 4) and provided with dust covers such as the one indicated at 72. Roller 34 is similarly equipped with ball bearings and dust covers. These dust covers are further provided with felt seals 74 to prevent dust entering the ball bearings and also to prevent the oil in the bearings from running out.

The lower jaw 12 carries a jaw component comprising a bracket 76 which is attached by means of bolts 78 and 80 carrying nuts 79 and 81. The bracket 76 is fitted with a series of arcuate tool holders such as 82, 84 and 86 to each of which is attached a curved and beveled steel staking knife 90. Any number of the tools 90 may be employed according to requirements, such number being restricted only by the length of the resilient endless band 30. As viewed in the drawings, the knives and holders lie in planes generally transverse to the free runs of the belt 30. To provide for the necessary adjustment of the tool holders 82, 84 and 86 the latter may each be provided, as shown in Fig. 3, with a dovetail formation 92 adapted for sliding engagement within a correspondingly formed groove or recess 94 in the bracket 76, set screws 96 being provided to secure the said holders in position after adjustment. In Fig. 2 the tool holders and blades or knives 90 are shown to be curved and all of the same radius, but the curvature of the different holders and knives may be of different radii. As an example, the tool holder 84 may have a larger radius than the holder 82, and the tool holder 86 may have a larger radius than the holder 84, the knives being made to fit. This latter arrangement increases the spreading action of the leather. If desired, however, straight tool holders and staking knives or even a combination of curved and straight tool holders and knives may be employed.

The opposed jaw components just described constitute a means for gripping and softening leather and are so relatively arranged that when they are closed, as shown in Fig. 1, the lower run of the endless resilient belt 30 is stretched over the upper, i. e., beveled edges of the knives 90 in such a way as in effect to provide a flexible bolster affording support for leather inserted between the jaw components when pressure of the knives is exerted against the leather.

The machine is provided with a horizontal table 100 having an opening 102 in which the knives 90 are arranged to operate. The endless resilient belt 30 is arranged to reciprocate and move bodily over and substantially parallel with the opening 102. The arrangement of the parts is such that when the jaws or jaw components close upon a work piece such as a skin 104 the staking means or blades 90 cause the belt 30 to be displaced a slight or desired distance into the zone between the rollers 32 and 34.

The end of the table 100 is provided with a rubber edging 105 against which the operator may hold or clamp a work piece 104 during treatment.

For the purpose of obtaining a very light softening action, such as may be required on glove leather, only two of the staking knives may be used and they may be arranged approximately

centrally between the two rollers 32 and 34 whereas for heavy staking the tool holder 86 may be moved nearer to a position directly below the center line of the roller 34, the tool holder 84 disposed directly below the center of the resilient belt 30, and the tool holder 82 placed as near as possible to a position beneath the center of the roller 32, that is, in the region where the belt 30 is firmly backed by the last-mentioned roller.

As the machine operates, the jaws 10 and 12 move rearwardly i. e. away from the operator with the jaw components closed, as shown in Fig. 1. On each return or forward stroke the jaws are opened and a leather work piece 104 is inserted between them and placed upon the work table 100 or a partially treated work piece is shifted to present a different portion of the work piece in position to be treated. It will be evident that during each rearward or working stroke the jaw components move relative to the work piece 104 and the latter is pulled over the staking knives 90 and treated to its extreme edge. The belt 30 and the knives 90 are moved rearwardly in performing their functions and, simultaneously, the rollers 32 and 34 rotate as the belt 30 moves bodily in contact with and relative to the upper side of the work piece 104. During each successive working stroke the work piece 104 is firmly held by the operator against the rubber end piece 105 on the edge of the work table. During successive return strokes, with the jaws open, the leather work piece 104 is moved so as to present fresh portions of its surface and substance for treatment by the staking knives 90.

Having thus described my invention, what I claim as new and desire to secure by Letters Patent of the United States is:

1. In a leather staking machine of the character described having two opposed and cooperating jaws, one of said jaws being provided with rollers supporting an endless resilient belt, and the other jaw carrying a staking tool arranged to press a skin to be treated against said belt.

2. In a leather staking machine of the character described, an endless resilient belt mounted upon rollers, means for varying the tension of said belt, said belt being arranged to move bodily in contact with and relative to one side of a skin, a staking tool arranged to press the said skin against the belt during said bodily movement, and means for adjusting the position of said tool relative to said belt.

3. In a leather staking machine of the character described, a table with a rectangular opening therein, an endless resilient belt mounted upon rollers and bodily movable over and substantially parallel with two sides of said opening, said belt being arranged to rotate the rollers by contact with a skin supported on the table because of said bodily movement, and staking means supported from the other side of the table and arranged to displace the belt a desired distance into the zone between the rollers during said bodily movement.

GUSTAV A. SCHETTLER.
